UNITED STATES PATENT OFFICE.

HENRY O'SHEA, OF JOHNSTOWN, PENNSYLVANIA, ASSIGNOR TO THE LORAIN STEEL COMPANY, OF PENNSYLVANIA.

RAILWAY-TRACK STRUCTURE.

SPECIFICATION forming part of Letters Patent No. 653,845, dated July 17, 1900.

Application filed November 7, 1899. Serial No. 736,134. (No model.)

To all whom it may concern:

Be it known that I, HENRY O'SHEA, of Johnstown, in the county of Cambria and State of Pennsylvania, have invented a new and useful Improvement in Railway-Track Structures, of which the following is a full, clear, and exact description, reference being had to the accompanying drawings, which form a part of this specification.

10 My invention has relation to certain new and useful improvements in railway-track structures—such as frogs, curve-crossings, straight crossings, and the like—in which two wheel-grooves or flangeways meet or intersect. Owing to the great wear to which structures of this kind are subjected at the points where said grooves meet or intersect, it has been customary in the best grade of such work to provide the structures with a removable plate made of some more durable material than the remainder of the structure and which might be taken out and replaced when necessary. Heretofore these plates, which are made of an expensive grade of material, when 25 so worn as to make it necessary to replace them have been entirely useless for further service and are thrown aside.

The object of the present invention is to provide a plate of this character which is reversible, so that when worn upon one side it may be removed and inverted and its life and period of usefulness be thereby doubled. I attain this object by a plate constructed and arranged in the manner hereinafter described, reference being had to the accompanying drawings, in which—

Figure 1 is a plan view of a railway frog or curve crossing embodying my invention. Fig. 2 is a detail view of the center plate removed. Fig. 3 is a section on the line 3 3 of Fig. 1. Fig. 4 is a detail view showing a different fastening device.

The letter A designates the track structure, which may in general be of any suitable construction, with a pocket B to receive the hardened center plate or member C. The structure shown is formed by casting together short rail sections or ends placed in suitable relation to each other, the pocket B being cored in the cast metal which unites said rail sections or ends. The plate C is formed with correspond-

ing wheel-grooves in both its upper and lower faces, so that when placed into either side of its grooves it will properly align with the rail-sections. The plate may be secured in place 55 in any suitable manner. A very convenient way of securing it is by means of wedges D; inserted through a recess at one side of the pocket and driven in opposite directions between the plate and the wall of the structure, 60 the said seat for said wedges being partly in the plate and partly in the wall of the structure. After the wedges have been seated some retaining material G, such as melted zinc, is poured over the same and around the 65 plate. This material can be readily cut away and the wedges unseated to remove the plate when it is desired to reverse it. The seats into which the wedges are driven are preferably formed with tapered converging walls, 70 as indicated in Fig. 1. The grooves upon the under side of the plate fill up with zinc or other retaining material used, as shown in Fig. 3, thus holding the plate securely in position against lateral movement should the 75 side wedges work loose. This material can be readily cut out of the grooves when the plate is reversed.

In order to permit the plate to be reversed, it must be symmetrical in shape with respect 80 to its longitudinal axis. In the drawings I have shown a hexagonal plate fitting a pocket of similar form; but it may obviously be rectangular or any other desired form.

When the meeting or intersecting grooves 85 are at different angles, the grooves upon the two sides will not be directly over each other, but will be so disposed that those on the under side will properly align when the plate is reversed. This is indicated by the dotted 90 lines in Fig. 2, which indicate the position of the grooves upon the under side of the plate.

In Fig. 4 I have shown a modified form of fastening in which the reversible plate is formed with a longitudinal beveled rib P at 95 the edge and the wall of the structure has a longitudinal recess P' of corresponding form. The rib P forms a bearing in both positions of the plate for the wedge D.

It is obvious that the invention may be applied to various track structures and is therefore not limited to the particular form and

arrangement which I have herein shown and described.

Having thus described my invention, what I claim, and desire to protect by Letters Patent, is—

- 5 1. A removable plate for railway-track structures, formed of hardened metal, and having wheel-grooves or flangeways formed in both its upper and lower faces, whereby it 10 may be reversed and used either side up, substantially as described.
- 15 2. In a railway-track structure, the combination with the body portion of the structure having a recess or pocket formed therein, of a hardened plate removably seated in said recess or pocket, and formed with wheel-grooves in both upper and lower faces whereby said plate may be reversed, substantially as described.
- 20 3. In a railway-track structure, the combination with a body portion having a pocket or recess therein, of a hardened plate removably secured in said pocket or recess and formed with wheel-grooves in both upper and lower faces, said plate being symmetrical with respect to its longitudinal axis, said plate also having at an edge thereof and equidistant from its upper and lower faces a seat for a fastening device, substantially as described.
- 25 4. In a railway-track structure, the combination with a body portion having a pocket or recess therein, of a hardened plate seated in said pocket or recess and formed with wheel-grooves in both upper and lower faces 30 arranged to aline with the wheel-bearing members of the structure, and soft retaining

material between said plate and the walls of said pocket or recess, said material also entering the grooves in the under side of the plate, said plate and the walls of said pocket or recess having seats for securing-wedges, the seat of the plate being equidistant from its upper and lower faces.

5. In a railway-track structure, the combination with the body portion of the structure 45 formed with a pocket or recess, of the symmetrical plate removably seated in said pocket or recess, and having wheel grooves and guards at both its upper and lower surface, the grooves on the under side of said plate 50 also forming seats for a retaining material.

6. In a railway-track structure, the combination with the body portion formed with a pocket having a recess in its side wall, of a reversible plate seated in the said pocket, and 55 having at its edge a wedge-seat opposite the said recess and equidistant from the upper and lower surfaces of the plate.

7. In a railway-track structure, the combination with the body of the structure having 60 a pocket therein, formed with a recess in its side wall, of a plate reversibly seated in said pocket and having an edge projection extending into the said recess, said projection being equidistant from the upper and lower surfaces 65 of the said plate.

In testimony whereof I have affixed my signature in presence of two witnesses.

HENRY O'SHEA.
